BRACE FOR AUTOMOBILE REAR DECKS OR
THE LIKEArthur Claud-Mantle, Trumbull, Conn., assignor
to The Bassick Company, Bridgeport, Conn., a
corporation of Connecticut

Application January 22, 1936, Serial No. 60,226

3 Claims. (Cl. 217—60)

The present invention relates to an improved brace for an automobile rear deck, or other structure where it is desired to provide a hinged closure which is supported in open position by a brace. In the usual type of brace heretofore in use it has been necessary in order to close the deck to break the brace from its locked supporting position by manually pressing upon one of the arms, which was both inconvenient and dangerous, as it required the use of one hand and the hand was apt to be pinched by the folding arms. As it is usually necessary to use one hand for supporting the deck as it is being closed and the other for breaking the brace the use of braces at both sides of the deck has not been practicable because of the necessity in such cases for use of both hands for breaking the two braces. Also the usual type of brace has been formed of a pair of hingedly connected arms which occupied considerable space and in which the hinge connection between the arms was subjected to considerable wear. Also this hinged type of brace exerted considerable pressure upon the hinged connection when supporting the deck closure in open position.

It is an object of the present invention to provide a brace in the form of a pair of telescopically connected arms adapted to be locked in an extended position to support the rear deck structure in open position, the supporting strain being thus exerted longitudinally of the two arms. A further object is to provide a brace which may be released from its extended locking position merely by slightly lifting the rear deck closure prior to closing it. It is further proposed to provide a brace which will be set for locking it by merely moving the rear deck closure to its upper limit position, so that no accuracy or skill will be required in causing the brace to lock.

A further object is to provide a brace of simple and inexpensive construction, which will be compact, in which the danger of injuring the hands is eliminated, and which may be readily installed upon existing types of rear deck structures.

With the above and other objects in view an embodiment of the invention is shown in the accompanying drawing, and this embodiment will be hereinafter more fully described with reference thereto, and the invention will be finally pointed out in the claims.

In the drawing:

Fig. 1 is a side elevation of a brace, according to my invention, and showing the same in closed position.

Fig. 2 is an inner edge view in closed position.

Fig. 3 is an inner edge view partially broken away and showing the relation of the parts set for locking through movement of the rear deck closure to its upper limit position.

Fig. 4 is an inner edge view showing the brace

in its normal open rear deck closure supporting position.

Fig. 5 is an inner edge view partially broken away showing the parts in the tripped position preliminary to closing the rear deck closure member.

Fig. 6 is a central vertical sectional view of the parts as shown in Fig. 5.

Fig. 7 is a plan view of the upper end of the lower arm showing the spring supporting cradle structure.

Fig. 8 is a central vertical sectional view thereof.

Fig. 9 is a horizontal sectional view taken along the line 9—9 of Fig. 6.

Fig. 10 is a horizontal sectional view taken along the line 10—10 of Fig. 6.

Similar reference characters indicate corresponding parts throughout the several figures of the drawing.

Referring to the drawing, the brace according to the exemplary illustrated embodiment of the invention comprises a lower arm 10, pivotally connected at 11 to a bracket 12 adapted to be secured to the interior of the side wall 13 of the rear deck compartment and an upper arm 14 telescopically connected to the arm 10, as will presently more fully appear, and pivotally connected at its upper end at 15 to a bracket 16 secured to the inner side of the rear deck closure member 17. It will be understood that the closure member 17 is hinged at its upper end to the rear deck in the usual manner.

At the upper end portion of the arm 10 a tubular guide body is secured, this guide body being of rectangular cross-section and comprising a base portion 18, side portions 19—19, inwardly bent top portions 20—20 bent into parallel spaced relation to the base portion, and guide flanges 21—21 bent outwardly at right angles from the portions 20—20 in spaced relation to each other. The upper extremities of the flanges 21 are spaced from the upper end of the top portions 20—20 and these portions above the flanges 21—21 are secured to the upper end of the arm 10 by means of extruded rivet studs 22—22 formed on the arm 10 and engaged in apertures in the portions 20—20 and riveted over to thus secure the guide body to the arm 10.

The arm 14 is slidably engaged in the space between the arm 10 and the base 18 of the guide body and has secured to its lower end a stop and trip member formed of sheet metal and substantially corresponding in cross-section to the cross-section of the guide body, comprising a U-shape trip portion 23 disposed in longitudinal alignment with the space between the flanges 21—21, top portions 24—24 bent outwardly from the portion 23, side portions 25—25, and base portions 26—26 bent inwardly from the portions 24—24.
